SUPERHEATED STEAM GARMENT FINISHER

Edward C. Maurer, St. Paul, Minn.

Application December 13, 1945, Serial No. 634,847

4 Claims. (Cl. 223—70)

1

This invention relates to a new and improved and useful apparatus for garment steaming, sterilizing, reshaping, drying and finishing device.

The object of this invention as a complete device is to provide an efficient apparatus for restoring dry cleaned or wet cleaned or wrinkled or shop worn garments to their proper size, shape and useable condition.

The principal object of this invention is to provide a new and novel apparatus for producing and distributing superheated steam and air under pressure to fabrics and garments of various kinds, sizes and styles. The advantage of using superheated steam in a device of this kind is that unless the steam employed in steaming a garment is dry or superheated it may and often does cause shrinkage and distorts the original shape of the garment, affects the color and also requires considerable time to dry or cure and in other ways not produce a new, fresh and satisfactory appearance.

A feature resides in providing an extremely simple and inexpensive unit wherein superheated steam may be directed to the garment supported by the unit. The superheated steam is momentarily directed to an under-form over which the garment is draped and the steam passes through this cloth form to the material of the garment, steaming the same with very slight moisture of the superheated steam. This operation causes the garment form to expand to fill out the garment in a similar manner as a garment is filled out by the wearer. After momentarily steaming the garment by superheated steam, the blower is put into operation and hot air quickly dries the garment. The garment is usually brushed lightly while it is being subjected to the superheated steam and while drying so that all of the wrinkles will readily be brushed out and the garment is finished in a few moments.

This unit is designed to overcome the requirement for skilled laborers to press the garment and furthermore, the pressing of the garment is really not good for the same because it has a tendency to press the material of the fabric down flat and even to make the same appear shiny unless a pressing cloth is interposed between the pressing iron. This unit overcomes these difficulties in an extremely simple manner.

The unit is provided with superheater coils which superheat live steam projecting against the same. A cylindrical shield surrounds the lower extremities of the coils and the outlet of the live steam. A blower is provided for directing air over the live steam outlet coils and the

2

shield causes the air to pass upward over the superheated coils.

A central standard projects from the frame extending over the superheating coils and which is secured to the base portion of the unit. This central standard supports the cloth undergarment form. It is also a feature to provide an inlet valve for live steam together with check valve means and a foot pedal for operating the inlet valve for the live steam. The base of the unit is cylindrical and is adapted to support arch-like pipe frame members which extend over the steam coils and which provide a support for the central standard. The central standard holds the under garment cloth form draped over the entire unit excepting the lower portion of the base and the blower unit which is positioned at one side of the cylindrical base, in close proximity thereto. The blower unit directs air into the base and up through the cylindrical shield within the arched framework of the unit. These features together with other details and objects of the invention will be more fully hereinafter set forth and defined.

In the drawings forming a part of the specification:

Figure 1 is a side view of my superheated steam garment finishing unit showing the under garment in dotted outline supported by the central standard which has a garment hanger at the top of the same.

Figure 2 is a plan view looking down on the unit shown in Figure 1.

Figure 3 is a section on the line 3—3 of Figure 2, showing an enlarged side elevation partly in section illustrating the operating parts of the unit and a portion of the blower housing.

Figure 4 is a back view in the opposite direction to Figure 1.

Figure 5 is a section on the line 5—5 of Figure 4 in the direction of the arrows.

The superheated steam garment finisher A is provided with a sheet metal base 10 which is hollow and to one side of which is connected by the flue 11, an air blower 12. The blower 12 may be operated by an electric motor 13, and is controlled by an electric switch 14.

Mounted on the base 10, I provide a frame 15 made of a series of pipes which extend upward from the base 10, and are formed with an arched top portion 16. The pipes 15 are connected by a suitable coupler at a common point 17 and projecting upward from the pipe coupler 17, I provide an upright pipe or rod standard 18. At the top of the standard 18, I mount a garment hanger

19 of any suitable form. Draped over the hanger is an under formed cloth shield 20. This shield 20 is similar to a garment and may be drawn in at the waist line 21 and is provided with a standard portion 22 which extends over the frame 15 covering the frame.

I provide steam superheater coils 23 positioned within the frame 15 and having the upper portion thereof supported by the coupler 24 directly below the connecting point 17. In this manner, the steam coils 23 are supported centrally within the frame 15.

Directly below the superheater steam pipes 23, I provide a live steam coil 25 connected with the steam inlet pipe 26. The coil 25 is formed with steam outlet holes 27. A valve 28 controls the flow of steam to the coil 25, and this valve is controlled by the foot pedal 29 which is connected by the lever 30 and the rod 31 to the steam inlet valve 28.

When the operator wishes to direct live steam out of the coil 25, she simply presses with her foot on the pedal 29, whereupon live steam is directed against the coils 23.

In the operation of the superheated steam garment finisher A, the air blower 12 is put into operation after the garment is steamed causing air to blow from the duct 11 through the base 10 and up over the coil 25. The draft of air from the blower causes the undergarment 20 to expand and remain in this form during the operation of the superheated steam garment finisher A.

Above the lower portion of the superheating coils 23, I provide a cylindrical shield 32. This shield confines the draft of air close to the superheating coils 23 and causes the air to pass quickly to the upper portion of the under garment 20. This shield also prevents the under-form from being drawn inward, or collapsed when the garment is being steamed.

The superheating steam coils 23 are connected to the steam intake pipe 26 so that steam is continuously passing through the coils 23. The intake pipe 26 extends upwardly to the top of the coil 23 and is co-axially located in relation to the coils 23. When the steam passes through the superheater coils, it then passes through the pipe 33 which is connected through the check valve 34 to the outlet pipe 35.

The lower end of the inlet pipe 26 is provided with a drain 36 which connects with the check valve 37 and which in turn is connected with the outlet pipe 35. Thus a built-in steam separator is provided which is of primary importance in the operation of my machine.

In operation, a garment to be finished by my superheated steam garment finisher is slipped over the under-form 20, draping down over the skirt 22. While the garment is in this position the operator of the machine A presses on the foot pedal 29 and momentarily directs live steam over the coils 23 which superheat the steam. While the garment is being steamed in this manner, it usually is brushed lightly so as to make the garment lie smooth over the under-form, and as soon as the operator releases the foot pedal 29, the live steam is cut off, and the air blower is put into operation. This causes air to pass over the superheater coils 23 which quickly superheat the air and dry the garment. The advantages of using superheated steam in a garment finisher of this character resides in the fact that the garment being steamed is not treated with too much moisture but rather is

treated by a dry steam rather than wet steam and therefore, the garment may be dried much quicker right while it is on the form 20.

Furthermore, by using superheated steam there is virtually little or no danger of shrinking the garment, or distorting its original shape, nor is the color of the garment affected. Furthermore, the time required to finish a garment is materially reduced as compared to old forms of finishers.

The form 20 may be contracted and reduced around the waist line 21, or at any other point (not shown) by any suitable means such as a draw-cord or any suitable means of contracting the diameter of the under form. Then, when it is desired to finish a larger garment, the form 20 may be expanded into the size of the dress being finished.

The construction of my garment finisher is extremely simple. The operation is simple, and anyone can learn to use the finisher A in a very short time. The period of finishing a garment is much shorter than with the old form of device. Furthermore, the live steam is confined into close proximity with the superheater coils and thus the action of superheating the steam takes place rapidly, and virtually reduces the possibility of live wet steam coming in contact with the garment. This is an extremely important feature of my garment finisher and it provides a long-felt want.

I claim:

1. A superheated steam garment finisher comprising a hollow base portion, an air blower in close proximity to said base and connected by an air flue, steam inlet and outlet pipes, a live steam outlet coil positioned above said base and having openings out of which live steam may escape, a valve and foot pedal for operating the same adapted to admit live steam to said live steam coil, a series of superheater steam coils connected to said steam inlet and positioned directly above said live steam coil with steam outlets, means for supporting the top of said superheater coils, and an arched frame formed by rod-like members supported in said base and extending over said superheater coils, a garment supporting rod projecting from the apex of said arched frame and adapted to support an under form over which a garment is adapted to be placed for finishing the same, and a cylindrical shield resting upon the top of said base and extending around a large portion of said superheater coils and surrounding said live steam outlet coil to direct the air from said blower to said superheater coils and to expand an under garment supported on said finisher.

2. A superheated steam garment finisher comprising concentric helical steam superheating coils connected to a source of live steam, a live steam outlet coil positioned directly below and within the diameter of said superheating coils, an air blower adapted to blow air over said superheating coils, a shield for confining the live steam from said live steam outlet coil into close proximity with said superheating coils, and means for supporting a garment adapted to be finished over said superheated steam garment finisher, and means to direct dry steam to the garment momentarily and then to direct hot air from said superheating coils to thoroughly dry the garment before it is removed from said superheated steam garment finisher.

3. A garment finishing unit adapted to receive garments, a garment support, an under form draped over said support, a superheating means

including concentric helical coils within the base portion of said garment finishing unit, a live steam outlet positioned directly below and within the outline of said superheating means, means for releasing live steam over said superheating means and in turn directing superheated steam to the garment to soften the same by dry superheated steam, and a cylindrical sleeve extending annularly around and in close proximity to said live steam outlet and the lower portion of said superheating means to confine the steam from said outlet in close proximity to said superheater means and overcome the vacuum at the base of said superheating means and live steam outlet and prevent the garment and form from being drawn inwardly during the steaming operation and drying of the garment.

4. A garment finishing unit comprising a cylindrical base, a lower cylindrical air chamber formed in said base, an air blower positioned to one side of said cylindrical air chamber, an electric motor for operating said blower to force air into said cylindrical air chamber, a double steam coil having a conical-like formation positioned above said cylindrical base, a cylindrical shield extending around the lower end of said steam coil and adapted to rest on the top of said cylindrical base, a circular live steam outlet po-

sitioned within said shield and closely adjacent the lower end of said double steam coil, a dome-like skeleton frame arched over said double coil and shield adapted to support the top of said double coil and to provide a central standard support for a garment hanger.
